UNITED STATES PATENT OFFICE.

JULES H. VENON, OF NEW YORK, N. Y.

DESIGN FOR A GOBLET OR SIMILAR ARTICLE.

40,710.

Specification for Design.

Patented May 31, 1910.

Application filed February 25, 1910. Serial No. 546,033. Term of patent 7 years.

To all whom it may concern:

Be it known that I, JULES H. VENON, a citizen of the United States, and resident of the city, county, and State of New York, have invented a new, original, and ornamental Design for a Goblet or Similar Article, of which the following is a specification, reference being had to the accompanying drawing, forming part thereof.

The figure is an elevation of a goblet, showing my new design.

The design comprises goblet or other glass

or crystalware or similar article, having a decoration composed of a series of flowers and leaves with elongated stems etched, engraved or otherwise, thereupon, substantially as shown in the drawing.

I claim:

The ornamental design for a goblet or similar article, as shown and described.

JULES H. VENON.
